TRAILING ANTENNA CONNECTOR

Theodore R. Trilling, Levittown, Pa., assignor to the United States of America as represented by the Secretary of the Navy

Filed Apr. 29, 1960, Ser. No. 25,807

9 Claims. (Cl. 343—707)

(Granted under Title 35, U.S. Code (1952), sec. 266)

The invention described herein may be manufactured and used by or for the Government of the United States of America for governmental purposes without the payment of any royalties thereon or therefor.

The present invention relates to reeling mechanisms for trailing-wire type aircraft antennas and more particularly to an improvement in electrical connector apparatus in a reeling mechanism for a trailing-wire type aircraft antenna.

Severe service conditions for a trailing-wire type antenna in modern aircraft have prompted the development of an improved means for electrically connecting the radio equipment in the aircraft to a trailing-wire antenna. Heretofore, one commonly known device for obtaining electrical contact consists of a metallic land or stationary bearing surface fixed in a fairlead. Tension on the antenna maintains a positive electrical contact between the antenna and the bearing surface. Another device uses roller bearing surfaces instead of stationary surfaces to reduce wear on the antenna and on the surfaces due to sliding friction. Both devices obviously obtain "noisy" electrical connection unless high contact pressure is maintained as by force-opposing bearing surfaces against opposite sides of the antenna. Extension and retraction of the antenna in the course of normal operations under such high contact pressures produces extensive wear on the antenna and on the bearing surfaces and frequently results in bending or kinking.

In the present invention an electrical connector apparatus is contemplated which provides a high pressure, low-impedance electrical contact between the radio equipment and the trailing wire antenna during radio operation and further includes means for removing all electrical contact while the antenna is being extended or retracted. The invention thereby minimizes "noises" due to poor electrical contact and obviates wear on the antenna and on the bearing surfaces.

Accordingly, it is an object of the present invention to provide a novel electrical connector apparatus for a trailing-wire antenna which maintains positive contact during radio operation and which is disconnected from the antenna while the antenna is being extended or retracted.

Another object of the invention is the provision of means capable of selectively making high pressure contact over a relatively long length of an aircraft trailing-wire antenna as it passes through a reeling mechanism fairlead.

A further object of the invention is directed to an improved arrangement of trailing-wire antenna guides and a wire cutter in combination with the electrical connector apparatus in a trailing-wire antenna fairlead.

These and other objects and many of the attendant advantages of the present invention will be readily appreciated as the same become better understood by reference to the following detailed description when considered in connection with the accompanying drawings wherein:

Fig. 1 illustrates, in a side elevation, the general ar-

2

angement of a reeling mechanism and a fairlead for a trailing-wire antenna mounted in an aircraft with the trailing-wire antenna in the fully retracted or reeled-in position;

- 5 Figs. 2a and 2b illustrate, by enlarged side views of a vertical cross-section of the fairlead shown in Fig. 1, the manner in which an electrical connector contained therein obtains high pressure contact over a prescribed length of the trailing-wire antenna; and
- 10 10 Fig. 3 represents an enlarged isometric view of a cut-away portion of the fairlead showing the electrical connector apparatus and associated elements in position for extending or retracting the antenna wire.

Referring now to the drawings, wherein like reference characters designate like or corresponding parts throughout the several views, there is illustrated in Fig. 1 an elevational view of a trailing-wire antenna reel mechanism, indicated generally by the numeral 10, for extending or reeling-out and for retracting or reeling-in a trailing-wire antenna 11 from an aircraft while in flight. The principal support member for the mechanism 10 comprises a tubular fairlead 12 extending through an outside wall 13 of the aircraft. The fairlead 12 is fixed to the wall 13 with the outer end thereof directed rearwardly in order that the antenna 11 is not subjected to any abrupt change in direction where it enters the slip stream at a flared portion 12'. The antenna 11 is wound on a supply drum or an antenna reel 14 which in turn is driven by a reversible electric motor 15 through a reduction gear means 16, the motor 15 and gear means 16 being fixed to aircraft structure or to the fairlead 12 by convenient support members. An electrical source, not shown, is selectively connected through a cable 16' to the motor 15 for rotating the reel 14 in a reeling or unreeling direction.

An enlarged isometric view of a cut-away portion of the fairlead 12 is shown in Fig. 3 wherein an electrical connector, indicated generally by the numeral 17, is shown in the position of electrical contact with the trailing-wire antenna 11. The connector 17 comprises the coaxial rings 18 and 19 electrically insulated from the fairlead 12 and connected to each other by two oppositely disposed resilient strips or elongated contacts 21 and 22. The contacts 21 and 22 are made of a spring material, preferably phosphor bronze, silver-plated for high electrical conductance, and formed in a manner which creates a spring bias that urges the confronting sides of the contacts 21 and 22 toward each other over the length L intermediate the ends thereof. The ring 18 is slidable within the fairlead 12 and is preferably constructed of Fiberglas or Teflon, and lower ring 19 of similar construction is fixed to the fairlead 12. An insulated electrical post 20 from the connector 17 extends through the fairlead 12 and connects to a remotely located radio transmitter-receiver 23 through an antenna connecting cable 24.

An enlarged side view of the contacts 21 and 22 is shown in Figs. 2a and 2b for demonstrating the manner in which positive electrical contact against the antenna 11 is achieved. In Fig. 2a, the antenna 11 is being extended or reeled-out, and an external force F is being applied to the movable ring 18 in a direction away from fixed ring 19 against the spring bias of contacts 21 and 22 thereby preventing the contacts 21 and 22 from touching the antenna 11 and causing sliding friction. When the external force F against ring 18 is removed, as shown in Fig. 2b, the contacts 21 and 22 are urged toward each other since ring 18 can now move toward ring 19 and finally cause contacts 21 and 22 to press against antenna 11. The total spring force of contacts 21 and 22 is sufficient to force the antenna 11 to deflect and follow the contour of the contacts 21 and 22 for at least the length

70

L. It should be noted that the contacts 21 and 22 are formed so that the point of maximum deflection of contact 21 is axially displaced from the point of maximum deflection of the contact 22 by the length L. It should also be apparent that the contact pressure can be very high without producing any substantial deflection of the antenna 11 because the contacts 21 and 22 merely oppose each other after they both fully engage the antenna 11. The spring force of contacts 21 and 22 can be augmented by additional means such as a solenoid spring 25. Hence, a high pressure connection is provided along a substantial length of antenna 11.

In addition to the ring and contact structure described, two guide rods 27 are fixed at diametrically opposite sides of the fixed ring 19 and extend through two correspondingly disposed guide tubes 28 fixed to the movable ring 18 and extending toward the reel-end of the fairlead 12. A drive yoke 29 interconnects the guide tubes 28 and serves as a common actuator plate for a solenoid armature rod 31. The rod 31 extends through a solenoid coil 32 internally fixed to the fairlead 12. The solenoid spring 25 is interposed between the coil 32 and the yoke 31 to bias the movable ring 18 toward the fixed ring 19 as described above.

Electrical leads 33 on the coil 32 are connected in parallel with the cable 16' whereby energization of the motor 16 in either direction will also energize the coil 32 and disengage the contacts 21 and 22 from the antenna 11. It is preferred that the ends of contacts 21 and 22 be electrically connected as by jumpers 35 thereby obtaining multi-path parallel circuits which tend to lower the overall impedance of the electrical connector 17.

A pair of radial brackets 34 fixed on diametrically opposite sides of the fairlead 12 pivotally support pulleys 36 to maintain the antenna wire 11 at the center of the movable ring 18. A similar pair of brackets 37 and pulleys 38 maintain the antenna 11 at the center of the fixed ring 19. Additional brackets 39 and pulleys 41 maintain a vertical center position of the antenna 11 within the fairlead 12. The pulleys 36, 38 and 41 are fabricated of an electrically nonconducting material such as Teflon. A "fish" or drogue 40 is attached to the outer terminal of the antenna 11 to insure sufficient initial drag and to prevent the antenna 11 from whipping against adjacent aircraft structure. The drogue 40 further minimizes droop when the antenna 11 is extended a prescribed amount by increasing the drag at the outer terminal of antenna 11.

A guillotine-type knife 42 is spring biased against a solenoid actuated latch 43 by a knife spring 44. Energizing a latch solenoid 46 releases the knife 42 and causes it to shear off and jettison the antenna 11 portion extending from the outer end of the fairlead 12. It is contemplated that a separate electrical supply, not shown, energizes latch solenoid 46 through electrical leads 47 whereby the antenna 11 may be sheared independently of the operation of the electrical connector 17.

Operation

The operation of the mechanism 10 will now be summarized with particular reference to Figs. 1 and 3 which show the trailing-wire antenna 11 in the fully retracted position and the electrical contacts 21 and 22 secured against the antenna 11. When the antenna 11 is to be extended or reeled out, the electrical power supply is connected through the cable 16' to the motor 15 to cause the motor to drive in a direction that will unreel the antenna 11. Simultaneously, the solenoid coil 32 is energized to overcome the forces of the spring 25 and the contacts 21 and 22 and to position the armature rod 31 and movable ring 18 away from fixed ring 19. The contacts 21 and 22 are thereby separated from the antenna 11 during reeling-out operation, as shown in Fig. 2a. After the antenna 11 has been extended the desired amount, the motor 15 and the coil 32 are deenergized

causing the antenna 11 to halt and permit the spring 25 and the contacts 21 and 22 to urge the movable ring 18 toward the fixed ring 19. Contacts 21 and 22 thereby re-engage the antenna 11 in the manner shown in Fig. 2b.

5 Conversely, energizing the motor 15 in a direction which causes the reel 14 to retract the antenna 11 also energizes the coil 32 to withdraw the contacts 21 and 22 from the antenna 11, while the retracting or reeling-in operation proceeds.

10 For emergency jettisoning or for other reasons where it is desirable to discard or separate the extended portion of the antenna 11 from the reeling mechanism 10, the electrical power supply is connected to the leads 47 thereby actuating the solenoid latch 43 which releases the knife 42 for severing the antenna 11.

15 It should be understood that the foregoing disclosure relates to only a preferred embodiment of the invention and that numerous modifications and variations may be made therein without departing from the spirit and scope 20 of the invention as set forth in the appended claims.

What is claimed is:

1. An electrical connector apparatus for a trailing-wire antenna extending therethrough, comprising: a pair of nonconductive rings adapted to be coaxially disposed 25 about the antenna, a first resilient strip contact connected at opposite terminals thereof to coinciding angular positions respectively on each of said rings, a second resilient strip contact connected at opposite terminals thereof to diametrically opposite angular positions respectively on 30 each of said rings, said resilient contacts adapted to be urged radially inward for engaging the antenna intermediate the terminals with maximum deflection of each of said contacts transversely displaced, means for applying a separating force to said rings whereby said contacts disengage when the antenna is passing through said apparatus, and means adapted for connecting said terminals to radio equipment.

2. An electrical connector apparatus for a trailing-wire antenna extending therethrough, comprising: a pair of nonconductive members adapted to be spaced apart along the antenna, a first resilient contact peripherally connected between said members, a second resilient contact peripherally connected between said members and opposingly disposed to said first contact, said contacts adapted 45 to be urged radially inward intermediate the ends thereof with deflection of each of said contacts transversely displaced, means for applying a force to said members whereby said contacts disengage when the antenna is passing through said apparatus, and means adapted for connecting electrical equipment to said contacts.

3. In an electrical connector apparatus for a wire extending therethrough, a pair of nonconductive members adapted to be disposed along the wire, two resilient contacts connected between said members and opposing disposed to each other, said contacts urged radially inward intermediate the ends thereof, means for applying a force to said members, and means for connecting said contacts to other electrical apparatus.

4. In an electrical connector apparatus for an extended 60 wire, a pair of flexible contacts opposingly urged against each other by a spring means and adapted to receive the wire therebetween, and means for removing said contacts while the wire passes through the apparatus.

5. In a trailing-wire antenna reeling mechanism for an 65 aircraft, the combination comprising: a cylindrical fairlead adapted to pass an extended trailing-wire antenna through the wall of the aircraft, an antenna reel and drive mechanism fixed at the inner end of said fairlead for extending or retracting the antenna, a drag means 70 attached to the free end of the antenna, a stationary non-conductive ring fixed to the inner wall of said fairlead, a movable nonconductive ring within said fairlead and coaxially slidably with respect to said stationary ring, a first flexible strip contact connected at the opposite terminals thereof at coinciding angular positions respective- 75

ly on each of said rings, a second flexible strip contact connected at the opposite terminals thereof to diametrically opposite angular positions respectively on each of said rings, spring means connected to urge said contacts radially inward for engaging the antenna intermediate the terminals with maximum deflection of each of said contacts transversely displaced, means for applying a force to said movable ring whereby said contacts disengage when the antenna is being reeled in or out, and means adapted for connecting said terminals to radio equipment.

6. Apparatus as set forth in claim 5 further comprising, in combination: a plurality of sheaves at each of said rings positioned for maintaining the antenna along the transverse axis of said fairlead.

7. In a trailing-wire antenna reeling mechanism for an aircraft, the combination comprising: a fairlead adapted to pass a trailing-wire antenna through the wall of the aircraft, a reel mechanism fixed at the inner end of said fairlead for extending or retracting the antenna attached at one end thereof, a stationary nonconductive member fixed to said fairlead, a movable nonconductive member within said fairlead, a first resilient contact peripherally connected between said members, a second resilient contact peripherally connected between said members and oppositely disposed to said first contact, said contacts adapted to be urged radially inward intermediate the ends of said contacts with maximum deflection of each

of said contacts transversely displaced, means for applying a force to said movable member, whereby said contacts disengage when the antenna is being reeled in or out, and means adapted for connecting electrical equipment to said contacts.

8. In a trailing-wire antenna reeling mechanism for an aircraft, the combination comprising: a fairlead adapted to pass an extended trailing-wire antenna through the wall of the aircraft, means for extending or retracting an antenna, two nonconductive members within said fairlead and coaxially slidable with respect to each other, two resilient contacts connected between said members and opposingly disposed to each other, said contacts urged radially inward intermediate the ends thereof, means for applying a force to said members, and means adapted for connecting said terminals to radio equipment.

9. Apparatus as set forth in claim 8 further comprising, in combination: a plurality of sheaves at each of said members adapted for centering the antenna within said 20 fairlead.
